UNITED STATES PATENT OFFICE.

ALEXANDER GROUNDWATER WALLS, OF PAISLEY, SCOTLAND.

SPINNING, TWISTING, WINDING, AND LIKE MACHINE.

1,193,321.

Specification of Letters Patent.

Patented Aug. 1, 1916.

Application filed January 10, 1914. Serial No. 811,361.

To all whom it may concern:

Be it known that I, ALEXANDER GROUNDWATER WALLS, a subject of the King of the United Kingdom of Great Britain and 5 Ireland, and residing at Paisley, Renfrewshire, Scotland, have invented a certain new and useful Improvement in Spinning, Twisting, Winding, and like Machines, of which the following is a specification.

10 This invention relates to tension devices for applying frictional drag to bobbins or spindles in spinning, twisting, winding and like machines for the purpose of maintaining tension on the yarn, *e. g.*, during the 15 operation of winding or unwinding, and has for its object to provide a finer adjustment of the drag than was heretofore possible and ready response to inequalities or to wear of the frictional surfaces without appreciably affecting the tension on the yarn.

In the accompanying drawing which illustrates the invention Figure 1 is a vertical section of the spring member of the drag-applying device; Fig. 2 is a vertical section 25 of the creel-peg for a winding-off bobbin with all of the members of the tension device in position. Fig. 3 is a plan view of the parts shown in Fig. 1. Fig. 4 is a plan of the base of the creel-peg showing the holding 30 and locking arrangements.

Referring to the drawing, 1 is a thin annulus bearing on one side a plurality of flat springs 2, fastened to the annulus at 3, but otherwise free throughout their length, and 35 having holes 4 by which they are located on a rotatable member hereinafter referred to. On the other side of the said annulus 1 is mounted an annular piece of felt 5 or like frictional material.

40 The fixed portion 6 of the creel-peg, hereinafter termed the spindle, is fixed to the creel stand in the usual way by means of a nut and washer. The base 7 of the spindle is recessed to receive a boss of the adjustable 45 member 8 and a retaining spring 9 for holding said member 8 in any position to which it may be set. The retaining spring 9 does not act in a number of notches, but bears 50 against a smooth surface, and thus is capable of retaining the member 8 in an infinite number of different positions. The screw 55 10 by pressing the retaining spring 9 against the boss of the member 8 serves as a locking device to prevent accidental readjustment.

55 The member 8 is screw-threaded internally to fit a correspondingly threaded part on the

spindle 6, thus providing for adjustment in an axial direction.

The rotating member 11, hereinafter termed the sleeve, is mounted between the shoulder 12 of the spindle 6 and a nut 13 locked against a shoulder 14 of the spindle, thus permitting of free rotation while remaining practically free from liability to shake in an axial direction. The bore of the 65 sleeve is of considerably larger diameter than the spindle but at each end is bushed with hard fiber or other suitable material to form a good fit on the spindle.

The sleeve 11 is formed at its bottom end 70 with a flange 15 presenting a recess 16 to receive the spring member which is mounted in the recess coaxially with the spindle by screws 17 which pass through the holes 4 in the free ends of the springs 2. The screws 75 17 are slightly smaller in diameter than the holes 4 to allow such slight movement as may be necessary to prevent the spring member from buckling as the springs are compressed.

80 The central orifice of the annulus 1 is so much larger in diameter than the portion of the spindle which it surrounds that the spring member and spindle can never come into contact. Similarly, the outer diameter 85 of the spring member is considerably smaller than that of the wall of the recess 16, so that there is no frictional contact which would affect axial movement.

In operation the member 8 is screwed 90 toward the sleeve till its polished face encounters the frictional surface 5 when a very slight drag will be obtained. Continued adjustment toward the sleeve will gradually increase the drag until a satisfactory tension is obtained on the yarn; then the adjustable member 8 may be securely locked by the screw 10. The spring member held by the points of its springs may thus be considered to be "floating" and is free to respond in an axial direction either to minute inequalities in the friction surface against which it acts or to slight wear of the friction surfaces without appreciably affecting the tension on the yarn. At the same time 100 the resiliency of the spring member provides for much finer adjustment than has hitherto been possible.

I claim:—

110 A tension device comprising in combination with two members rotatable relatively to one another, a spring member for applying

frictional drag in opposition to such relative rotation, said spring member provided with spring elements each apertured at its free end, said spring elements projecting from the plane of one face of said annulus, said annulus provided on the opposite face with a body of frictional material, and retaining elements of less diameter than the apertures in said spring elements for securing said

spring elements to one of said relatively 10 rotatable members.

In testimony whereof I have signed my name to this specification in the presence of two subscribing witnesses.

ALEXANDER GROUNDWATER WALLS.
